United States Patent Office

Des. 208,470
Patented Sept. 5, 1967

208,470

BURIAL VAULT

Edward A. Madej, Verona, Pa., assignor to Nationwide
Vault and Manufacturing Company, a corporation of
Pennsylvania

Filed July 21, 1966, Ser. No. 3,173

Term of patent 14 years

(Cl. D19—1)

Fig. 1.

Fig. 2.

Fig. 3.

Fig. 4.

FIGURE 1 is an exploded isometric view of a burial vault showing my new design;

FIGURE 2 is an assembled isometric view thereof;

FIGURE 3 is a reduced scale end elevational view thereof; and

FIGURE 4 is a reduced scale side elevational view thereof.

The top and bottom are identical, as are the two sides and the two ends.

I claim:

The ornamental design for a burial vault, as shown and described.
